UNITED STATES PATENT OFFICE.

GEORGE W. BEADLE, OF STAMFORD, CONNECTICUT, ASSIGNOR TO COLUMBIA
GRAPHOPHONE MANUFACTURING COMPANY, OF BRIDGEPORT, CONNECTI-
CUT, A CORPORATION OF DELAWARE.

CORRECTION DEVICE FOR PHONOGRAPHIC MACHINES.

1,403,584.

Specification of Letters Patent. Patented Jan. 17, 1922.

Application filed April 27, 1920. Serial No. 377,111.

To all whom it may concern:

Be it known that I, GEORGE W. BEADLE, a citizen of the United States, residing at Stamford, in the county of Fairfield and 5 State of Connecticut, have invented certain new and useful Improvements in Correction Devices for Phonographic Machines, of which the following is a full, clear, and exact description.

10 This invention relates to phonographic machines of the character used for dictation purposes and has particular reference to the means for imparting information to the transcriber concerning the spoken words 15 engraved in the wax tablet.

It is an object of the invention to simplify devices of this character and to make possible the incorporation of the same into existing machines without detracting from the 20 appearance thereof or requiring the redesigning of the same.

The invention consists, briefly speaking, in the provision, in lieu of the usual scale bar, of a bar having at one end a table over 25 which the index member may be moved. Overlying the table is a pencil guide, the same being preferably in the form of an arch stamped up from the table. One edge of the bar is provided with a channeled 30 guide preferably in the form of segments stamped up from either side of the plate. This guide is adapted to straddle one longitudinal edge of the index member to prevent the same from buckling or collapsing as it 35 is pushed over the table. A bracket on the carriage serves as a support for one end of the index member and to push the same over said table. Other features of the invention will appear from a detailed description 40 thereof taken in connection with the accompanying drawing, in which,

Fig. 1 is a plan view showing the application of my invention to a well known form of dictation machine;

45 Fig. 2 is a vertical section along the line 2—2 of Fig. 1; and

Fig. 3 is a view taken on line 3—3 of Fig. 2.

Only so much of the phonograph machine 50 is shown and described as will suffice to show the application of the invention thereto.

The base of the machine is indicated by numeral 12. Below the base is a motor box

13 containing mechanism (not shown) for imparting rotation to the mandrel 14 on 55 which the record tablet 15 is mounted and for moving the sound-box carriage 16 longitudinally of said tablet.

Rising from the base is a pair of standards 17 having forwardly projecting arms 18. 60 Extending between these standards is a slotted tube 19 along which the carriage is movable. This tube is adapted to contain a screw-shaft (not shown) for causing traveling movement of said carriage axially of the 65 tablet 15 upon the suitable manipulation of the lever 20 which serves to operatively connect the carriage to said screw-shaft. The carriage is prevented from rotating on said tube by means of a stabilizer arm 21 which is bifurcated at its lower end to straddle a rod 22 extending between said standards. Along 70 said tube and rod the carriage may be freely moved by hand when the lever 20 is in neutral position.

The arms 18 projecting forwardly from the upper ends of the standards normally carry a scale (not shown) along which a pointer (not shown) moves as the carriage 75 travels.

In carrying out my invention, I employ 80 said arms for supporting a bar 23, which at one end has a laterally projecting table 24 over which the index sheet 25 is adapted to be moved by the carriage through the instrumentality of a bracket 26 mounted on 85 the carriage 16.

For supporting the index member between the table and bracket, I provide a channeled 90 guide, along the upper edge of the bar 23. This guide is preferably formed by stamping up on either side of the bar, a series of segments 27 from a bent over portion of the same. This guide is therefore 95 in the nature of a series of fingers which straddle one longitudinal edge of the index sheet.

The upper part of the bracket 26 is flat and has a spring clip 28 which serves to frictionally secure the index member to the 100 bracket. The bracket is further provided with a flange 29 which defines the correct relation of the index member with respect to the channeled guide on the bar 23 and also with respect to the table 24.

105 Overlying the table is an arch 30 which

thus forms a gateway for the index member. This arch is preferably stamped up from the table 24 and has a downturned end 31 for deflecting the said member as it passes through the gate. While it is desirable that the index member be confined against lateral movement as it passes over the table, it will be readily appreciated that means other than that described and shown 10 may be employed.

Overlying said table is a pencil guide which, in the present instance, is the edge of the arch 30. This pencil guide is preferably not a right line but rather takes the form 15 of a wave-like edge, the crest being midway the width of the index member. This arrangement serves to prevent the pencil from being accidentally drawn across the whole 20 width of the sheet and is simpler than providing, for the same purpose, a raised longitudinal beading in the index sheet as is proposed in some devices known in the art.

In inserting the index member or strip into the machine it is merely necessary to 25 place one edge of the same in the channeled pathway formed by the projecting fingers on the bar and to insert the other end of same under the clip of the bracket. The marginal flange on the bracket insures that 30 the index strip will be properly positioned with respect to the channeled guide in the bar and that it will pass freely under the arch over the table without binding. In removing the strip it is merely necessary to 35 grasp the free end which extends under the tail-like projection of the arch and pull the same out of the clip.

It will now be seen that I have provided a simple but practical correction device and 40 have positioned the same so as not to detract from the appearance of the machine as a whole. The point at which the pencil marks are adapted to be made on the index sheet is at the extreme right end of the machine and hence is in a very convenient position 45 for the average user.

While the invention has been described in considerable detail this is not to be taken as a limitation of the invention; the scope of 50 the same will appear from the appended claims.

What I claim as new and desire to secure by Letters Patent is:

1. In a phonographic machine, the combination with the traveling carriage, of an index member, a table over which said member may be moved, a bracket on said carriage for supporting one end of the said member, and means between said table and bracket 55 preventing buckling of said member.

2. In a phonographic machine, the combination with the traveling carriage, of an index member, a table over which said member may be moved, a bracket on said carriage for supporting one end of said mem- 60 ber, and means between said table and bracket preventing buckling of said member.

3. In a phonographic machine, the combination with the traveling carriage, of an index member, a table over which said member may be moved, a bracket on said carriage for supporting one end of said member, and means between said table and bracket 70 preventing buckling of said member forming an opensided supporting channel along the line of travel of the same.

4. In a phonographic machine, the combination with the traveling carriage, of an index member, a table over which said member may be moved, a bracket on said carriage for supporting one end of said member, and means between said table and bracket 75 preventing buckling of said member comprising a channeled guide straddling one edge thereof.

5. In a phonographic machine, the combination with the traveling carriage, of an index member, a table over which said member may be moved, a bracket on said carriage for supporting one end of said member, a channeled guide between said table and bracket straddling one longitudinal 85 edge of said member, and means on said bracket preventing lateral displacement of said member out of said guide.

6. In a phonographic machine, the combination with the traveling carriage, of an index member, a table over which said member may be moved, a bracket on said carriage for supporting one end of said member, means between said table and bracket 90 preventing buckling of said member, and means on said bracket and table preventing lateral displacement of said member.

7. In a phonographic machine, the combination with the traveling carriage, of an index member, a table over which said member may be moved, a bracket on said carriage for supporting one end of said member, an arch overlying the plane of said table 100 and forming a gateway for said member.

8. In a phonographic machine, the combination with the traveling carriage, of an index member, a table over which said member may be moved, a bracket on said carriage for supporting one end of said member, an arch overlying the plane of said table 110 and forming a gateway for said member, said arch having a downwardly turned portion for deflecting the free end of said member downwardly.

9. In a phonographic machine, the combination with the traveling carriage, of an index member, a table over which said member may be moved, a bracket on said carriage for supporting one end of said member, means between said table and bracket 120 preventing buckling of said member, and a pencil guide in offset adjacent relation to said table.

10. In a phonographic machine, the combination with the traveling carriage, of an index member, a table over which said member may be moved, a bracket on said carriage for supporting one end of said member, means between said table and bracket 125 preventing buckling of said member, a pen- 130

cil guide in offset relation to said table, and means preventing lateral displacement of said member as it moves over said table.

10. In a phonographic machine, the combination with the traveling carriage, of an index member adapted to have movement as the carriage travels, and a stationary pencil guide overlying said index member and having a wave-like edge.
11. In a phonographic machine, the combination with the traveling carriage, of an index member adapted to have movement as the carriage travels, and a stationary pencil guide overlying said index member and having a wave-like edge, the crest thereof being midway the width of the index member.
12. In a phonographic machine, the combination with a traveling part of the machine, of an index member disposed at one side of the part, and a support over which said member is pushed by said part.
13. In a phonographic machine, the com-

bination with a traveling part of the machine, of an index member disposed at the advancing side of the part, and a support over which said member is pushed by said part.

14. In a phonographic machine, the combination with a traveling part of the machine, of a flexible index member disposed at the advancing side of the part, a support over which said member is pushed by the part, and means adapted to prevent buckling of said part.

15. In a phonographic machine, the combination with a traveling part of the machine, of an index member having movement proportionately to the movement of the traveling part, a support over which said member is moved, and a stationary indicator formed integral with the support.

In testimony whereof, I affix my signature.

GEORGE W. BEADLE.
